UNITED STATES PATENT OFFICE.

WILLIAM F. IRISH, OF ANDERSON, SOUTH CAROLINA.

DISPLAY HOOK.

Application filed December 14, 1925. Serial No. 75,302.

This invention relates to display hooks whereby garments and the like may be readily supported for the display purpose upon show cases, cabinets, clothing or merchandise shelving, etc. etc.

The primary object of the present invention is to provide a hook that is readily attachable or detachable in order that the same may be disposed at any convenient point upon the support, regardless of what it may be, and in order that garments upon hangers may be detachably associated therewith for display purposes.

With the foregoing and other objects in view as the nature of the invention is better understood, the same comprises the novel constructed display hook hereinafter more fully described, shown in the accompanying drawing and claimed.

In the drawing:—

The figure is a perspective view of a display hook constructed in accordance with the present invention, the same being shown as actually associated with a support which in the present instance is illustrated fragmentarily as being a clothing or merchandise cabinet.

Now having particular reference to the drawing, my novel display hook constitutes the provision of a single length steel rod of relatively small diameter that is so bent as to provide a relatively elongated arm 8 with respect to a right angularly extending finger 9, that is formed by bending the rod adjacent its upper end. The inner end of the finger 9 is provided with a downwardly projecting point 10 that may be forced into the surface of a counter, show case, cabinet, or other suitable support for the hook indicated generally by the reference character A.

Slidably disposed upon the arm portion 8 of the hook is an extending bracket 11 that is composed of a single strip of relatively narrow sheet metal, that is bent intermediate its ends as to provide an eye 12 slidable over the arm portion 8 of said hook. The material forming the bracket is bent outwardly in a converging manner from the eye portion 12 to provide legs 13—13, the ends of which

are bent outwardly as to provide counter, 50 cabinet, or shelving front wall engaging feet 14—14 that are padded upon their inner faces for preventing marring of said walls.

The provision of bracket 11 will obviously maintain the hook in proper position upon 55 its support and to bend the arm 8 of the hook from engaging said wall of the support, and for maintaining the same in proper spaced relation therewith.

The lower end of the arm 8 of the hook 60 is formed into an eye 15 in order that the usual hook B of a garment hanger C may be engaged and supported therein, said eye extending in a direction parallel to the finger 9 of the hook in order that the garment 65 hanger will hang in a position parallel to the support upon which the hook is engaged.

It will thus be seen that I have provided a highly novel, simple, and efficient form of display hook, that is well adapted for all 70 the purposes intended and even though I have herein shown and described a specific construction is nevertheless to be understood that minor changes may be made therein without departing from the spirit and scope 75 of the appended claim.

Having thus described the invention, what I claim as new is:—

In a hook of the class described, a single 80 length rod, the upper portion thereof being bent laterally to provide an elongated vertical arm portion, and a relatively short finger portion, the outer free end of said finger portion being disposed downwardly and terminating in a point adapted for engagement with a support, an eye formed on the lower free end of said vertical arm adapted to provide a support for a garment hanger, said eye being disposed in substantially the same plane as the aforementioned finger portion, and a brace slidably on the arm portion and adapted for engagement with said support for maintaining the arm in a vertical manner and in spaced arrangement with respect to its support. 90

In testimony whereof I affix my signature.

WILLIAM F. IRISH.
